WELDER'S HELMET

Joseph Doran, St. Louis, Mo., assignor to
Joseph J. Doran, Barrington, Ill.

Application November 22, 1944, Serial No. 564,599

4 Claims. (Cl. 2-8)

1

The invention relates to hoods or shields, and more specifically to devices of this class worn by workers in various industries where the eyes may be harmed either by intense light or by particles of foreign matter flying into the eyes, welders being a large group generally wearing such devices.

The invention has among its objects, the production of such a device that will be neat and simple, sturdy in construction, easy to operate, relatively low in cost, safe in operation, and which will be otherwise satisfactory and efficient for the uses to which the device is applicable.

A further object of this invention is to provide means in such a welder's hood, that will enable him to lift the darkened panel normally covering the sight opening, with a simple downward movement of his chin, and to close said opening with a like, but shorter movement of his chin.

An added object of the invention is to so construct the device of the kind described, so that after the darkened panel has been lifted by the movement of the chin, to open the sight opening, it will be automatically maintained open, all without the use of the hands, for as long as desired, and also without holding the chin on the actuating means, and when it is desired to again close the darkened panel, a movement of the chin, but lesser in distance moved, will release said panel and permit the panel to be automatically retrieved to normal, closed position.

Many other objects and advantages of the construction herein shown and described, and uses mentioned, will be obvious to those skilled in the art to which this invention appertains, as will be more clearly apparent from the disclosures herein given.

In the drawings, wherein like reference characters indicate like or corresponding parts throughout the views,

Figure 1 is a perspective view of the window-operating mechanism, with the hood and the cover part of the housing, the full lines indicating the positions of the various parts at the end of window lifting movement;

Figure 2 is a vertical cross-sectional view of the same, with a fragment of the hood shown;

Figure 3 is a skeleton elevational view of the parts that directly engage the window-actuating lever, the full lines indicating the parts at the end of lift, and the dotted lines indicating the same immediately prior to the start of lift; and

Figure 4 is a perspective view of the device mounted on the hood, ready for wear.

Referring more particularly to the drawings, wherein I have illustrated a preferred embodiment of my invention, there is shown a hood or shield 1, preferably of rectangular transverse cross-section and of such size that it will readily permit the entry of the wearer's head into the same.

In order to fit with more comfort, and permit adjustment for a range of body sizes, I have provided shoulder-engaging elements 2 slidably adjustably connected to the sides of the hood, somewhat as shown, and thus it is possible to vertically adjust the hood so as to enable the wearer to more comfortably wear the same and permit of efficient vision through the sight opening of the hood.

Workers doing welding and similar tasks, find that there is quite a bit of discomfort connected with such work, not only on account of the envelopment of the head by the hood, but on account of injurious or odorous fumes and gases that tend to rise upwardly of the hoods and are breathed by the worker. This action is not only harmful in itself, but tends to make for inefficient work, and I have so constructed the hood that these objections are overcome and efficiency of the workman is increased, through means associated with the hood, for forcing the air downwardly to thus prevent the fumes from rising within the hood, but cooling the head, back, chest and shoulders of the worker.

To this purpose, I have mounted an electrically-driven fan or blower 3 adjacent the top of the hood, the motor 4 being suitably provided with the lead-wires 5 to a source of electrical energy, and the blower discharging at 6 through an opening in the top of the hood, somewhat as indicated.

The air is thus forcibly circulated, being driven downwardly through the hood, about the face, neck, back, shoulders, chest and adjacent portions of the body of the wearer, and discharged from the bottom of the hood. Obviously, this current of air adds greatly to the comfort of the wearer as well as promoting his increased efficiency.

During the course of work, it is often requisite to inspect the piece being welded, to read a blueprint, and for many other purposes, and it is a great waste of time to take off the hood, or to even manually lift the darkened sight-opening cover to do this.

To overcome this, I have arranged means so that the hands need not be released from the tools or piece of work being operated on, but upon

the contrary this means permits the chin of the wearer to lift and to close the dark panel.

In order to accomplish this result, I have positioned a frame vertically in the front of the hood, this frame preferably being composed of spaced substantially parallel sheets of rigid material 7-7 having the sight opening 8 therethrough and whereby the worker may observe things exteriorly of the hood the ends of the frame being enlarged to form upright channels 45-45. The frame has a bottom channel 9 with a cut-out 10 substantially centrally of said bottom, and through which a lever 11 extends, as will be hereinafter described.

A panel 12 of dark glass is mounted to slide vertically between the sheets 7-7 of the frame, normally resting adjacent the channel 9 when the hood is worn and the sight opening is darkened.

Lifting of the panel 12 is constantly resisted by one or more springs 13 or the like placed in the channels 45-45, the same bearing on said panel and tending to return or retrieve the lifted panel to its lowered or closed position whenever the force maintaining the panel lifted is released. Pieces of uncolored glass or other suitable transparent material 14-14, are removably mounted in the frame, parallel to and preferably at either side of and are stationary relative to said panel 12, in order to protect the latter against accidental breakage, dirt and grease, etc., and to protect the eyes against the danger of any particles of foreign matter flying into the hood while the panel is lifted, and these elements 14-14 may be replaced easily in the event that they become damaged.

The lever 11, previously mentioned, is movable up and down through the opening 10, and has considerable side play so as to permit of angular movement, said lever being pivotally connected at its upper end to the bottom edge of the panel 12, or as shown, to a cross bar 15 supporting the latter, while the lower end of said lever extends through an opening 42 in a fixedly mounted circular flange 46, and said lower end of the lever is shaped to form a transversely offset tooth or foot 16. A series of pins or projections 17, there being four in the modification illustrated, are arranged at equal circumferential distances apart on the periphery of a rotary disk 18, the latter being journaled on the shaft 19 for rotary movement. A cover 47 may be removably held in place against the flange 46, on the shaft 19, as shown in Fig. 2.

When the foot end 16 of the lever 11 is in engagement with the pin or projection 17 that is farthest to the left as shown in dotted lines in Fig. 3, and the disk is rotated clock-wise, the lever 11 will be actuated upwardly, moving the dark panel 12 upwardly against the pressure of the retriever springs 13, and will maintain said panel lifted as long as the pin is held interlocked with the said lever. A spring 19' is mounted between said lever and the bar 15 to constantly urge or press the toothed end of said lever to the left.

Cam portions 20 are constructed on the periphery of said disk 18, one adjacent each of said pins 17, with their radially outermost points closest their cooperating pin and with their peripheral surfaces gradually decreasing radially, somewhat as shown.

A plurality of teeth 21-21 are fixed to said rotary disk 18 to move together therewith, these teeth being substantially alike, equi-distant circumferentially from one another, and at like

radial distances from the rotational axis of the disk, and said disk is rotated by lateral pull applied on any one of these teeth, as will now be described.

5 A plate 22 is provided with an inclined slot 23 therethrough, said slot preferably closed at the ends, there being an actuating pawl 24 successively operably engageable with said teeth 21-21 in sequence, said pawl being carried by a spring arm 40 fixed at its other end to the underside of said plate 22. A second, cooperating pawl 25, mounted on a spring arm 41 fixed to any stationary element, has its toothed end projecting into the path of rotational travel of the teeth 21-21. Said spring arm 41 is fixed at one end to an annulus 48 that is fixed to the flange 46 to extend radially inwardly thereof.

When the plate 22 is urged to the right, through a chin-controlled means to be hereinafter described, it will be guided downwardly as well, through engagement of its diagonal slot 23 with the shaft 19, and one or more fingers 26, 27 may be mounted on any stationary element as for example the annulus 48, to closely overlie said plate so that the latter is guided to move substantially in a plane.

An arm 28 is fulcrumed intermediate its ends to said annulus 48, as at 29, the upper end of said arm being pivotally connected to the plate 22, preferably adjacent the right-hand of the latter, and a spring may be interposed between the lower end of said arm and a fixed element 30, to thereby constantly urge said arm to press its upper portion towards the left.

When the various elements are in their normal positions, that is to say, with the dark panel closed, the spring 30 will have moved the arm 28 so as to position the plate 22 to a point farthest left, as shown in dotted lines in Fig. 1, whereat the pawl 24 will be interlocked with the tooth 21 brought uppermost, while the pawl 25 will be interlocked with the tooth 21 that is to the left of and next adjacent said highest tooth. Thus, the disk will be held at each quarter turn on a single pull of said arm 28.

Now that the various parts are in the positions recited, an upward thrust on the lower end of the arm 28 will pivotally move the other end of said arm to the right (against the tension of the spring 30), the plate 22 being actuated downwardly and to the right, and with the pawl 24 pulling the highest tooth to rotate the disk through a quarter turn, while at the same time the foot of the lever 11 is actuated upwardly and to the right from the position shown in dotted lines in Fig. 3, to lift the panel. At the limit of upward movement of the lower end of the arm 28, and releasing of said arm, the spring 30 will retrieve said plate to its normal position shown in dotted lines in Fig. 1, while the foot end of the lever 11 will remain interlocked with the pin then at highest point, to hold the dark panel lifted.

To cause said dark panel to lower to normal position, after it has been lifted to opened position, I again urge the lower end of the fulcrum lever 28 upwardly, in the same manner as that employed for lifting the panel, but only a slight upward lift of the lever 28 is necessary, and only sufficient to pull the pin then highest slightly to the right, whereupon the foot 16 moves slightly to the right to engage and stop at one edge of the casing slot 42, and as soon as said last-mentioned pin has been actuated free of engagement with the foot, the spring 19' throws the lever slightly in the opposite direction (that is, to the left); and

the panel retriever springs 13 immediately thrust the said panel to its lowered position. The cam portion 28 prevents the lever 11 from dropping straight down as the panel drops, but on the contrary directs said lever toward the left as the latter drops.

The lever 11 then re-engages the pin to the left, next following the one just released (see Fig. 3), whereupon an upward pressure on the lower end of the arm 28 will re-lift the panel through lifting of said lever 11 in the same manner as just described.

In order that the hands need not be used for any operation of the panel moving means, a chin-controlled operating means has been used. A lever 31 is pivoted intermediate its ends, as at 32, to a fixed bracket carried by the framework of the device, and an extension 33 is hinged at 34 to an end of said lever 31, in such a manner to stop pivotal movement of the extension after the latter and said lever 31 are in alignment, but permit of folding the extension up toward the disk. This increases the clearance in the hood to permit the lever extension to pass the face of the wearer of the hood, and after donning the hood, the extension may be lowered to operative position. A small platform 39 may be fixed adjacent the free end of said extension, and is adapted to be in juxtaposition to the bottom of the chin when the mouth of the wearer is in normal, closed position. However, a downward movement of the chin, as by opening of the mouth the required amount, will depress said platform the half-inch or so required for operation of the device.

In order to transmit the chin movement of the platform to the fulcrum lever 28, and subsequent operation of the panel-lifting and lowering mechanism, the inner end of the lever 31 is connected by a universal joint 35 to the lower end of a link 36, the latter being pivotally connected at its upper end to said fulcrum arm 28.

Obviously, with a mechanism of the kind described, the panel may be lifted and lowered by operation of the chin while wearing the hood, the movement of the chin being in the same direction for both the opening and the closing of the dark panel, namely downwardly, so that it is not necessary for the wearer to remember whether or not he ought bring his chin up or bring it down, as would be the case if the mechanism required opposed movements for lowering or opening of the panel.

Although other types of means may be used to secured the hood to the head, I have found that an extremely comfortable and simple form is that shown, wherein a resilient pad is mounted in the rear wall of the hood, to receive the rear of the head, and a resilient band is mounted in the front wall of the hood to engage the forehead, these elements being indicated at 43 and 44 respectively.

Having thus described my invention, it is obvious that various immaterial modifications may be made in the same without departing from the spirit of my invention; hence I do not wish to be understood as limiting myself to the exact form, arrangement, construction and combination of parts herein shown and described, except as limited by the state of the art to which this invention appertains and the claims hereunto appended.

What I claim as new and desire to secure by Letters Patent is:

1. A device of the kind described, comprising a head hood provided with a panel normally clos-

ing the sight opening through the hood, rotary means having a plurality of circumferentially spaced projections thereon to lift said panel, chin-controlled means for operating said rotary means, and means releasably holding said panel in opened position after one full movement of said chin-controlled means and retrieving the same to closed position immediately after the commencement of the next like movement of said chin-controlled means.

2. In a hood of the kind described, adapted to cover the wearer's head and provided with a panel normally closing a sight opening through the hood, a rotary disk having a plurality of circumferentially spaced projections thereon, a lever operable between said panel and disk and engageable by said projections in sequence as the disk is rotated, chin-operated means movable successively in the same direction to open and to close said panel and including retriever means operable to close said panel after said lever is disengaged by any of said projections.

3. In a hood of the kind described and adapted to be worn over the head and provided with a movable panel at a sight opening, a rotary disk having circumferentially spaced projections, a lever pivoted to said panel and successively engageable by said projections to lift said panel as the projection in engagement therewith is actuated uppermost, means for advancing said disk circumferentially the distance substantially equal to the space between adjacent projections, means for retrieving said last-mentioned advancing means after each actuation, and chin-controlled means operable by pressure of the chin thereagainst for operating said disk-advancing means and for operating said retrieving means.

4. A device of the kind described, comprising a head-receiving hood having a sight opening therethrough, a panel closing said opening and urged to normal position therein by a yieldable means, a rotary member supported by the hood and having a series of circumferentially spaced projections thereon, means connected to the panel and positioned for successive engagement by said projections, chin-controlled means operatively movable in one direction, means operative by said chin-controlled means and successively engageable with said rotary member for moving the same through a predetermined angular range for engagement of one of said projections with said first means to move said panel out of said opening and retain same in such position, and means operative upon a second movement of said chin-controlled means in the same direction and of less extent for conditioning said panel for sight-opening closing movement under the action of said yieldable means.

JOSEPH DORAN.
